H.-SAUTER.
REGISTERING HOOK.
APPLICATION FILED JULY 12, 1919.

Patented Apr. 13, 1920.

UNITED STATES PATENT OFFICE.

HERMAN SAUTER, OF CHICAGO, ILLINOIS, ASSIGNOR TO LATHAM AUTOMATIC REGISTERING COMPANY, OF CHICAGO, ILLINOIS, A CORPORATION OF ILLINOIS.

REGISTERING-HOOK.

1,336,487.

Specification of Letters Patent. Patented Apr. 13, 1920.

Application filed July 12, 1919. Serial No. 310,405.

To all whom it may concern:

Be it known that I, HERMAN SAUTER, a citizen of the United States, residing at Chicago, in the county of Cook and State 5 of Illinois, have invented certain new and useful Improvements in Registering-Hooks, of which the following is a specification.

My invention relates to what are known in the printer's art as "register hooks," which 10 are devices having a base adapted to be locked in the chase of a printing form and equipped with a hook or engaging member adapted to interlock with the edge of a plate to hold it in the form for printing. The object of my invention is to provide a simple 15 and strong device of this character in which the hook member has an adjustable and swiveled support in the base, to the end that the plate may be placed angularly with respect to the page if desired, or that it may 20 adjust itself to make contact with the edge of a plate on which the type characters or illustration thereon do not lie square with the edges of the plate. My invention 25 consists in the form, arrangement and organization of the parts of the novel register hook hereinafter described and which I have invented and designed with the above object in view, the essential elements thereof being 30 more particularly pointed out in the appended claims defining my invention.

In the accompanying drawing forming part of this specification, Figure 1 is a plan view of a portion of a printer's form showing 35 the manner in which the hook is used; Fig. 2 is a perspective of a complete base and hook; Fig. 3 is a perspective of one of the two members of the sliding block in which the hook proper is mounted; Fig. 4 is a longitudinal vertical section of the device, showing 40 a fragment of a plate with which it is adapted to coöperate; and Fig. 5 is a rear view of the device.

The same reference characters indicate the 45 same parts in all the figures of the drawing.

My invention is more particularly designed to be used with and as part of a plate-mounting system in which the printing plates are beveled or undercut in a well-known manner around their margin in order 50 to adapt them to coöperate with hooks adjustably mounted on sliding blocks arranged in bases which are spaced in the form by means of plain bases or blocks of various 55 standard dimensions. Briefly describing a

printer's form of this description, (see Fig. 1), the chase 1 is arranged to receive the plain bases 2 and slotted bases 3 in which the plain or ordinary form of hooks 4 are slidingly mounted, the hook members being adjustable in the bases 3 by the actuation of screws 5. Bases of varying numbers of ems are used, and also spacing blocks of various thickness to partially fill the spaces of the slotted blocks and serve as abutments for the 60 screws to bear upon, as may be needed to make up a particular form. These hooks 4, and also the swiveled hooks to which my present invention relates, are spaced and arranged according to the requirements of the 65 particular case, six hooks being ordinarily used to secure each plate, one at each end (if the plate be oblong in shape) and two on each side.

The slotted base in which my novel swiveled hook is mounted may be the same as the base 3 heretofore used with the hooks 4 above mentioned, and consists of a metal block 6 (see Figs. 2 to 5, inclusive) having rectangular faces, and channeled or grooved 70 to form a slideway for the reception of the two-part sliding block 7^a, 7^b. The block is divided on a plane lying transversely of the direction of movement of the block in the slideway, and its parts are firmly secured 75 together by suitable means 8, as by screws or by rivets, four being employed for the purpose in the present instance. A longitudinal screw-threaded bore 9, engaged by the locking screw 10 corresponding to the 80 screws 5 before mentioned, is formed in the block, and by turning the slotted head of the screw with a suitable implement provided for the purpose, the swiveled hook, which will next be described, can be forced 85 into secure engagement with the plate which it is designed to secure.

The hook 11 (see Fig. 4) has an upper flat portion 12 formed with a beveled overhanging engaging face 13 arranged to engage the beveled or undercut recess of the plate 14, and a depending short pivot 15 which is peripherally flanged or headed at its bottom. The block members 7^a and 8^a are formed with a pivot bearing adapted to 90 receive the headed pivot of the hook, one-half the bearing being formed in each member, so that the parts may be readily assembled and the block members secured together.

It will be seen from the description above given that my screw swiveled register hook is simple and extremely sturdy in construction and that it is admirably adapted to sustain long continued hard service.

I claim:

1. A device of the character described comprising a base member formed with a slide-way, a separable divided block in said

10 slide-way having its members formed with a longitudinal screw threaded bore, said block having a pivot bearing formed partly in each member of the block, a hook having a headed pivot engaging said bearing, and

15 a locking screw engaging said bore.

2. A device of the character described comprising a base member formed with a slide-way, a block consisting of two separable members arranged in said slide way and

20 formed with a longitudinal bore, said block having a pivot bearing formed one-half in each of said members, a hook having a headed pivot engaging said bearing, and a locking screw engaging said bore.

3. A device of the character described 25 comprising a base member formed with a slide-way, a block consisting of two members divided on a transverse line arranged in said slide-way and formed with a longitudinal bore, said block having a pivot bearing formed one-half in each of said members, a hook having a headed pivot engaging said bearing, and a locking screw engaging said bore.

30 4. A device of the character described comprising a base member formed with a slide-way, a block consisting of two members divided on a plane at right angles to said slide-way and formed with a longitudinal bore, said block having a pivot bearing 40 formed one-half in each of said members, a hook having a headed pivot engaging said bearing, a locking screw engaging said bore, and a series of rivets arranged parallel with said locking screw and arranged to secure 45 said block members together.

HERMAN SAUTER.
